CLAIM

We claim the ornamental design for the “name card holder”, as shown and described.

DESCRIPTION

FIG. 1 is a rear facing perspective view of a name card holder;

FIG. 2 is a front view thereof;

FIG. 3 is a rear view thereof;

FIG. 4 is a right side view thereof;

FIG. 5 is a left side view thereof;

FIG. 6 is a bottom view thereof; and,

FIG. 7 is a top view thereof.

The broken lines illustrate portions of the name card holder that form no part of the claimed design.
